Illinois Glass Company, a corporation of Ohio

Filed Aug. 20, 1964, Ser. No. 81,382

Term of patent 14 years

(Cl. D58—5)

FIG. 1

FIG. 2

FIG. 3

FIG. 4

FIGURE 1 is a side elevational view of a jug showing my new design;

FIGURE 2 is a top plan view thereof;

FIGURE 3 is a front elevational view thereof; and

FIGURE 4 is the back elevational view thereof. The side not shown is the same as the side shown.

The dominant features of my design reside in the portion shown in full lines.

I claim:

The ornamental design for a jug, substantially as shown and described.
